(57) **CLAIM**

The ornamental design for a quick connect receptacle, as shown and described.

DESCRIPTION

FIG. 1 is a top view of a quick connect receptacle showing my new design;

FIG. 2 is a front elevational view thereof, the rear elevational view being identical;

FIG. 3 is a right side elevational view thereof, the left side elevational view being identical;

FIG. 4 is a bottom view thereof;

FIG. 5 is a perspective view thereof; and,

FIG. 6 is a front, cross-sectional view thereof in the direction of line 6-6 of FIG. 1.

The broken line portion of the figure drawings is included to show unclaimed subject matter only and forms no part of the claimed design.
